UNITED STATES PATENT OFFICE.

GEORGE K. COOKE, OF NEW YORK, N. Y., ASSIGNOR TO D. SACKETT
MOORE, OF SAME PLACE.

GAS-BURNER.

SPECIFICATION forming part of Letters Patent No. 361,674, dated April 26, 1887.

Application filed November 18, 1886. Serial No. 219,274. (No model.)

To all whom it may concern:

Be it known that I, GEORGE K. COOKE, a citizen of the United States, residing at New York, in the county and State of New York, 5 have invented a new and Improved Gas Burner, of which the following is a specification.

This invention relates to that kind of gas-burners in which a small secondary burner is placed alongside of the main burner, a small 10 flame being kept burning in the secondary burner when the gas is turned off from the main burner. When the supply to the main burner is turned on, the flame from the secondary burner ignites the gas, and thus the 15 main burner can be lighted at any time without a match.

The invention consists in the various features of improvement hereinafter more fully pointed out.

20 In the accompanying drawings, Figure 1 is a vertical central section of my improved gas-burner. Fig. 2 is a side view of the valve-plug. Figs. 3 and 4 are side views of the sleeve *i*. Fig. 5 is a vertical central section of the burner, showing the main burner turned off.

The letter *a* represents the main burner, and *b* the secondary burner, placed side by side and entering at their lower end a tapering valve-seat, *c*, adapted for the reception of the 30 tapering plug-valve *d*. The lower side of the valve-seat *c* is entered into by the supply-pipe *e*, having a branch, *f*, that also enters the valve-seat. The secondary burner *b* is shorter than the main burner *a*, and the latter is surrounded 35 by a mica chimney, *g*, into which the secondary burner *b* enters, while the main burner projects above such chimney, as shown. The mica chimney is covered by a perforated cap, *h*, that permits the products of combustion 40 from the burner to escape.

Within the valve-seat *c* there is placed a tubular sleeve, *i*, preferably made of brass and embedded snugly into the metal of the valve-seat *c*. This sleeve *i* is introduced into the 45 mold in which the valve-seat is cast, and in this way I obtain a tight fit for the valve-plug

d without boring out the interior of the valve-seat.

A small portion of the sleeve *i* is cut away, as shown at *j*, Fig. 4, said cut-away portion 50 being filled up in the process of casting by the metal from the valve-seat, and thus said sleeve is properly locked in place and is prevented from working loose. Four holes are made in the sleeve *i*, to register with the 55 burners *a b* and with the pipes *e f*.

The valve-plug *d* is provided with one straight transverse perforation, *k*, in line vertically with the parts *a e*. It is also provided with a groove, *m*, partly encircling the plug 60 *d* and in line with the secondary burner *b* and branch *f*, so as to connect the parts and conduct the gas from the branch into the secondary burner. The groove *m* communicates by a spiral groove, *l*, with the perforation *k*. 65

The operation of the parts is as follows: When the supply from the main burner is turned off, the gas will enter from pipe *f* through groove *m* to burner *b*, Fig. 5; but when the valve *d* is turned to bring perforation *k* in line with the parts *a e*, and to thus permit the gas to enter the main burner, the burner *b* will be cut off from branch *f*, and the gas from such branch will enter through the groove *e* into the main burner *a*, and will aid 75 in maintaining the flame.

I am aware that it is not new in gas-burners of the general character herein described to employ a valve-plug having an aperture diametrically through it adapted to register with 80 the main burner and a supply-pipe when the main burner is turned on, said plug also having an oblique groove leading from said diametrical aperture to a groove adapted to register with the secondary burner and an offset 85 passage, *f*, when the main burner is turned off. I am also aware that in faucets it is old to apply bushings to form smooth valve-seats in the body of the valve. I therefore broadly disclaim such devices. 90

What I claim is—

1. The combination of burners *a* and *b* and

pipes *e f* with the conical valve-seat *c* and inclosed perforated tubular sleeve *i*, having cut-away portion *j*, and with the perforated plug-valve *d*, having grooves *l m*, substantially as specified.

2. In a gas-burner having a primary burner, *a*, a secondary burner, *b*, and a body provided with gas-passages, as described, the combination of the conical sleeve *i*, perforated at

four points, cut away at *j*, and embedded into the metal forming the body of the burner, and a valve-plug, *d*, having gas-passages *k l*, in and fitted into said sleeve, substantially as described.

G. K. COOKE.
